(57) **CLAIM**

I claim the ornamental design for a paddle blade, as shown and described.

DESCRIPTION

FIG. 1 is a front perspective view of a paddle blade showing my new design;

FIG. 2 is a rear perspective view of the paddle blade shown in FIG. 1;

FIG. 3 is a front elevation view of the paddle blade shown in FIG. 1;

FIG. 4 is a rear elevation view of the paddle blade shown in FIG. 1;

FIG. 5 is a right side elevation view of the paddle blade shown in FIG. 1, the left side being a mirror image of the right side;

FIG. 6 is a top plan view of the paddle blade shown in FIG. 1;

FIG. 7 is a bottom plan view of the paddle blade shown in FIG. 1;

FIG. 8 is a cross-sectional side elevation view of the paddle blade taken at line 8-8 shown in FIG. 4;

FIG. 9 is a cross-sectional top plan view of the paddle blade taken at line 9-9 shown in FIG. 4; and,

FIG. 10 is a cross-sectional top plan view of the paddle blade taken at line 10-10 shown in FIG. 4.

The pole attached to the paddle blade is shown in broken lines to indicate that it forms no part of the claimed design. The remaining broken lines depict portions of the article that form no part of the claimed design.
